UNITED STATES PATENT OFFICE.

CHARLES I. D. LOOFF AND FREDERICK A. KNAPP, OF BROOKLYN,
NEW YORK.

MECHANICALLY-ACTUATED ORGAN.

SPECIFICATION forming part of Letters Patent No. 760,884, dated May 24, 1904.

Application filed October 4, 1902. Serial No. 125,956. (No model.)

To all whom it may concern:

Be it known that we, CHARLES I. D. LOOFF and FREDERICK A. KNAPP, both citizens of the United States, and residents of the city of New York, borough of Brooklyn, in the county of Kings and State of New York, have invented a new and Improved Mechanically-Actuated Organ, of which the following is a full, clear, and exact description.

The invention relates to self-playing musical instruments in which the sounding devices are controlled from a movable note-sheet.

The object of the invention is to provide a new and improved mechanically-actuated organ arranged to play a number of long pieces of music successively without requiring a change of note-sheet; the organ being more especially designed for use on merry-go-rounds and in halls, pleasure-grounds, and other places of amusement.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a transverse section of the improvement on line 1 1 of Fig. 3. Fig. 2 is an enlarged transverse section of the same on the line 2 2 of Fig. 3. Fig. 3 is a front elevation of the improvement, the casing and main shaft being shown in section. Fig. 4 is an enlarged cross-section of the wind-chest and the device for actuating the wind-chest valve, and Fig. 5 is a diagrammatic view of the shifting-cam for the carriage and the arrangement of the series of rows of notes on the note-sheet.

In a suitably-constructed casing A is journaled the main shaft B, extending transversely, and carrying at one end a crank C or other means for imparting a continuous rotary motion to the shaft B either by hand or by power. On the shaft B, within the casing A, is secured a bevel gear-wheel D, in mesh with a bevel gear-wheel D', secured on one end of a

roller E, journaled in suitable bearings in the casing A and carrying at its other end a bevel gear-wheel D², in mesh with a bevel gear-wheel D³, secured on a transverse shaft B', journaled in the casing A in horizontal alinement with the main shaft B. Thus when the main shaft B is rotated a rotary motion is given by the gear-wheels D and D' to the roller E, and the latter by the gear-wheels D² and D³ rotates the shaft B'.

Over the roller E passes an endless note-sheet F, also passing over rollers E' and E'', journaled within the casing A, as plainly indicated in Fig. 1, the roller E' being located a distance in the rear of the roller E, so that the note-sheet F extends horizontally from the roller E to the roller E', and over this horizontal portion are arranged levers G, provided at their forward ends with points G', adapted to fall into the notes formed on the sheet F in the shape of slots or the like, as indicated in the drawings. The levers G are located one alongside the other and extend transversely and are pressed on by springs G'', so as to cause the forward or point ends of the levers to swing downward when a point G' registers with a note on the note-sheet. The levers G are fulcrumed on a carriage H, mounted to slide across the sheet F in the direction of its width for the purpose hereinafter more fully described, and the rear end of each lever G carries the stem I' of a valve I, controlling a valve-seat J', connecting a pressure-chamber J with an air-chamber K, having an opening K' leading to the atmosphere, the said opening K' being controlled by a valve I'', held on the stem I' of the valve I. The pressure-chamber J is connected by a duct J² with a wind-chest L, having valves L', controlling openings L², leading to chambers N, connected with individual sounding devices O, formed of pipes or the like, as indicated in Fig. 1. Each air-chamber K connects by a duct or pipe P' with a diaphragm-chamber P, (see Figs. 1 and 4,) containing a diaphragm P'', of leather or other suitable flexible material, and on the under side of this diaphragm P'' rests the head or button Q' of a rod Q, mounted to slide in a suitable bearing ar-

ranged in the top of the chamber N, the lower end of the said rod Q engaging the top of the valve L', normally held to its seat by a spring L³ to close the opening L². The wind-chest 5 L is supplied with air by a pipe R' from a bellows R, connected by links R² with cranks B² on the shafts B and B', so that when the latter are rotated, as previously described, the bellows R is actuated to pump air into the 10 wind-chest L.

Now when the instrument is in use and the several parts are in the position shown in Figs. 1 and 4 and a swinging motion is given 15 to a lever G by its spring G² at the time its point G' registers with a note in the note-sheet F then the valve-stem I' moves the valve I from its seat J' and moves the valve I² onto the opening K' to close the air-chamber K to the atmosphere and to connect the 20 said chamber with the pressure-chamber J. Now air from the wind-chest L passes by the duct J² to the pressure-chamber J and through the seat J' into the chamber K through the 25 pipe P' and the diaphragm-chamber P to force the diaphragm P² therein downward, thereby moving the rod Q in a like direction to swing the wind-chest valve L' open and connect the wind-chest L with the corresponding chamber N to sound the sounding device O corresponding 30 to the lever G actuated at the time. As the note-sheet F travels on, the point G' is forced upward on reaching the end wall of the note, so that the lever G moves back to its former 35 position and in doing so moves the valve I into a closed position on the valve-seat J' and the valve I² into an open position relative to the opening K', so that the chambers J and K are disconnected from each other and the air from the chamber K exhausts by the opening K' to 40 the atmosphere. The diaphragm P² is by this arrangement relieved of pressure within the chamber P, and consequently the spring L³ closes the valve L' and in doing so the valve pushes the rod Q upward, thus moving the 45 diaphragm P² back into its former uppermost position. (Indicated in Figs. 1 and 4.)

The note-sheet F is provided with a series of rows of notes F', F², F³, F⁴, F⁵, F⁶, F⁷, and F⁸, forming a plurality of pieces of music, preferably of different characters, the rows being arranged consecutively and the pieces of music forming the said plurality being arranged in a different playing order from the consecutive arrangement of the series of rows. Now 55 in order to bring the points G' and levers G in alinement with the rows of notes for each piece of music it is necessary to shift the levers relative to the sheet F, and for this purpose the carriage H, carrying the levers G, 60 is made to slide in the direction of the width of the note-sheet F. The carriage H is provided at one end with rods H' and H² and is mounted to swing at its rear end on a rod H³, carried by the casing A. (See Fig. 1.) A 65 spring H⁴ bears against the end of the carriage

opposite that from which the rods H' and H² project, as shown in Fig. 3, to force the carriage in the direction of the arrow a'. The rod H' engages the peripheral surface of a cam S at the top thereof, while the end of the rod H² engages the face of a cam S', rotating in unison with the cam S, the said cams S and S' being preferably fastened together and journaled on a pin S², carried by the casing A. The cams S and S' receive an intermittent rotary motion controlled by the note-sheet F, and for this purpose the following mechanism is provided: On one of the cams S or S' is secured a ratchet-wheel T, engaged by the hinged end T' of a pawl T², fulcrumed at T³ on the casing A and normally held in an uppermost position by the action of a spring T⁴. (See Fig. 2.) An upward swinging motion is given to the pawl T² by a cam T⁵, secured on the shaft B, so as to cause the pawl T² to impart an intermittent turning motion to the ratchet-wheel T and the cams S and S'. In order to swing the pawl T² downward at the proper time, the following device is provided: The pawl T² is connected with a pneumatic U, secured to the casing A, the pneumatic being connected by a pipe U' with an exhaust-chamber V, having a valve-seat V' opening into the pressure-chamber J, previously described, the said exhaust-chamber 95 also having an opening V² leading to the atmosphere. The valve-seat V' is controlled by a valve W, secured on a valve-stem W', also carrying a valve W² for closing the opening V² at the time the valve W moves off its seat V' 100 to connect the chambers J and V with each other. The valve-stem W' is connected with a lever G³, similar to the levers G, and pressed on by a spring G⁴ to engage its point G⁵ with one of a series of notes F⁹, formed on one end 105 of the note-sheet F and separate from the notes F', F², F³, F⁴, F⁵, F⁶, F⁷, and F⁸, previously described. Normally the valves W and W² are in the position shown in Fig. 2; but when the point G⁵ drops into a note F⁹ 110 and the spring G⁴ imparts a swinging motion to the lever G³ then the latter causes the stem W' to move the valve W off the valve-seat V' and to move the valve W² into a closed position to disconnect the exhaust-chamber V 115 from the atmosphere. Air from the pressure-chamber J now passes through the opening V' into the chamber V and from the latter by the pipe or duct U' into the pneumatic U to impart a swinging motion to the pawl T², so 120 that the hinged end T' thereof engages the next following tooth of the ratchet-wheel T and at the same time the pawl T² places the spring T⁴ under tension. Now when the point G⁵ moves out of a note F⁹ the lever G³ is returned to its former position, the valve W is moved to its seat V', and the valve W² again moves into an open position to allow the air to escape from the chamber V and pneumatic U, and the pawl T² by the action of the 125 130

cam T^5 imparts a rotary motion to the ratchet-wheel T , and consequently to the cams S and S' . Now when the cams S and S' are turned by the pawl T^2 , as described, then the carriage H and the levers G and G^3 thereon are lifted upward by the action of the rod H' on the cam S to disengage the points G' and G^5 from the note-sheet and then the end of the rod H^2 moves in contact with the incline on the cam S' to shift the carriage H across the sheet F in the direction of the width thereof to bring the points G' in alinement with another row of notes and to bring the point G^5 in alinement with the next note F^6 . By means of the cam S' and the spring H^4 the carriage is shifted in both directions—that is, say, first from the left to the right and then from the right to the left—and step by step, so as to bring the points G' in register with all the rows of notes in the note-sheet.

In order to accomplish this result, the carriage H is shifted in such a manner that when the points G' are first in alinement with the rows of notes F' and the sheet F has made a complete revolution then the cam S' shifts the carriage so as to bring the points G' in alinement with the rows of notes F^8 , and after this piece of music has been played and the note-sheet F has made another revolution then a further shifting of the carriage H takes place by the action of the cam S' to bring the points G' in alinement with the rows of notes F^5 . On the next shifting of the carriage the points G' are brought in register with the rows of notes F' , and on the next shifting of the carriage the points register with the rows of notes F^8 , and then the return movement of the carriage is brought about by means of the spring H^4 , and on the first shifting of the carriage the points G' are brought in register with the rows of notes F^6 , on the next shifting with the rows of notes F^4 , then with the rows of notes F^2 , and finally the points G' are brought back to the first row of notes F' , and then the above-described operation is repeated. From this it will be seen that the plurality of pieces of music on the note-sheet F have their notes arranged in series of rows, the rows being arranged consecutively and the pieces of music forming the said plurality being arranged in a different playing order from the consecutive arrangement of the series of rows. Now by the arrangement described the single music-sheet F contains a large number of pieces of music, and as there is almost no limit to the length of the endless sheet it is evident that exceedingly long pieces of music can readily be arranged on the sheet, and hence it is not necessary to frequently replace the note-sheet, as is the case with self-playing instruments as heretofore constructed.

It is understood that each of the cams S and S' is provided with alternately-arranged inclined and straight surfaces, the inclines of the cam S registering with the straight faces of the cam S' and the inclines of the cam S'

registering with the straight faces of the cam S . Thus while the carriage H is lifted by the cam S the rod H^2 engages with its ends the straight faces of the cam S' , and when the rod H' rests on the straight peripheral portions of the cam S then the rod H^2 is engaged by the inclines of the cam S' to shift the carriage H across the sheet F and bring the points G' to the desired position relative to the rows of notes, as above described, and when this has been accomplished the carriage H is again lowered by the action of the following inclines of the cam S acting on the rod H' . When the carriage H has finally reached its lowermost position, the intermittent rotary motion of the cams and the actuating ratchet-wheel T ceases, and the carriage H remains in this position until the next piece of music has been played—that is, until the sheet F has completed its revolution.

Having thus described our invention, we claim as new and desire to secure by Letters Patent—

1. A music-sheet having several series of note characters representing respectively different tunes, and a musical instrument having sounding devices controlled by the music-sheet and having a step-by-step shifting mechanism acting in both directions relative to the width of the music-sheet, for executing the pieces of music in both directions, as set forth. 90

2. A musical instrument having a traveling note-sheet, spring-pressed levers controlled by the notes on the note-sheet, pneumatic controlling devices, actuated by the said levers, sounding devices controlled by the said pneumatic controlling devices, and a shifting mechanism acting in both directions relative to the width of the music-sheet, as set forth. 100

3. A musical instrument having a traveling note-sheet provided with series of rows of notes, a carriage slidable transversely of the note-sheet, spring-pressed levers fulcrumed on the carriage and controlled by the notes on the note-sheet, pneumatic controlling devices actuated by the said levers, a wind-chest having connection with bellows and having its valves controlled by the controlling devices, and sounding devices controlled by the said wind-chest, as set forth. 105 110

4. A musical instrument having a controlling device for a wind-chest valve, comprising an air-pressure chamber connected with a pressure-supply, such as the wind-chest, an air-chamber communicating with the pressure-chamber and having an opening to the atmosphere, valves, one for controlling the communication between the said air-chamber and the pressure-chamber and the other for closing the opening of the air-chamber, means 120 for operating the said valves, a diaphragm-chamber connected with the air-chamber and containing a diaphragm, and a connection between the diaphragm and the wind-chest valve, as set forth. 125 130

5. In a musical instrument, a wind-chest, a sounding device, a valve for controlling the admission of air to the sounding device from said chest, an air-pressure chamber, a duct connecting the pressure-chamber with the wind-chest, an air-chamber having an opening communicating with the pressure-chamber and an opening leading to the atmosphere, valves, one for controlling the opening establishing communication between the pressure-chamber and air-chamber and the other for controlling the opening of the air-chamber leading to the atmosphere, the valves being arranged on a stem one below the other, a note-sheet, levers controlled by the note indications of the said sheet and with which the stem of the said valves is connected, a diaphragm-chamber, a duct connecting the diaphragm-chamber with the air-chamber, a diaphragm 15 in said chamber, and a rod connecting the valve of the wind-chest with the diaphragm, as set forth.
6. A musical instrument having a traveling note-sheet provided with series of rows of 20 notes, a carriage slidable transversely of the sheet, spring-pressed levers fulcrumed on the carriage and controlled by the notes on the said note-sheet, pneumatic controlling devices controlled by the said levers and controlling 25 the sounding devices, and shifting means for automatically shifting the carriage, to bring the levers successively in alinement with the different series of rows of notes on the note-sheet, as set forth.
- 30 7. A musical instrument having a traveling note-sheet provided with series of rows of notes, a carriage slidable transversely of the sheet, spring-pressed levers fulcrumed on the carriage and controlled by the notes on the 35 said note-sheet, pneumatic controlling devices controlled by the said levers and controlling the sounding devices, and shifting means for automatically shifting the carriage, to bring the levers successively in alinement with the different series of rows of notes on the note-sheet, as set forth.
- 40 8. A musical instrument having a traveling note-sheet provided with series of rows of notes, a carriage slidable transversely of the sheet, spring-pressed levers fulcrumed on the carriage and controlled by the notes on the 45 said note-sheet, pneumatic controlling devices actuated by the said levers and controlling the sounding devices, and shifting means for automatically shifting the carriage, to bring the levers successively in alinement with the different series of rows of notes on the note-sheet, as set forth.
- 50 9. A musical instrument having a traveling note-sheet provided with series of rows of notes, a carriage slidable transversely of the sheet, spring-pressed levers fulcrumed on the carriage and controlled by the notes on the 55 said note-sheet, pneumatic controlling devices comprising two cams engaging the carriage, one for lifting the carriage and its levers and the other for moving the carriage lengthwise, and cam-actuating means for intermittently rotating the cams, controlled from the note-sheet, as set forth.

the carriage and its levers and the other for moving the carriage lengthwise, as set forth.

9. A musical instrument having a traveling note-sheet provided with series of rows of notes, a carriage slidable transversely of the sheet, spring-pressed levers fulcrumed on the carriage and controlled by the notes on the said note-sheet, pneumatic controlling devices actuated by the said levers and controlling the sounding devices, shifting means for automatically shifting the carriage, to bring the levers successively in alinement with the different series of rows of notes on the note-sheet, the said shifting means being arranged to move the carriage step by step in both directions relative to the width of the music-sheet, the said shifting means comprising two cams engaging the carriage, one for lifting the carriage and its levers and the other for moving the carriage lengthwise, and cam-actuating means for intermittently rotating the cams, controlled from the note-sheet, as set forth.

10. A musical instrument having a traveling note-sheet provided with series of rows of notes, a carriage slidable transversely of the sheet, spring-pressed levers fulcrumed on the carriage and controlled by the notes on the said note-sheet, pneumatic controlling devices controlled by the said levers and controlling the sounding devices, shifting means for automatically shifting the carriage, to bring the levers successively in alinement with the different series of rows of notes on the note-sheet, the said shifting means being arranged to move the carriage step by step in both directions relative to the width of the music-sheet, the said shifting means comprising two cams engaging the carriage, one for lifting the carriage and its levers and the other for moving the carriage lengthwise, and cam-actuating means for intermittently rotating the cams, controlled from the note-sheet, the said cam-actuating means comprising a ratchet-wheel, a pawl for the same, a pneumatic on the pawl and having connection with an air-chamber, a pressure-chamber, a valve mechanism for connecting the chambers with each other and for closing the air-chamber to the atmosphere, and a lever connected with the said valve mechanism and controlled by the note-sheet, as set forth.

11. A musical instrument having a carriage carrying note-sheet levers, and means for supporting and shifting the carriage, said means comprising a face-cam and a peripheral cam, both cams rotating in unison, the cams being engaged by arms on the carriage, as set forth.

12. A musical instrument having a carriage carrying note-sheet levers, means for supporting and shifting the carriage, said means comprising a face-cam and a peripheral cam, both cams rotating in unison, the cams being engaged by arms on the carriage, and means for imparting an intermittent rotary motion to the said cams from the note-sheet, as set forth.

13. A musical instrument having a carriage carrying note-sheet levers, means for supporting and shifting the carriage, said means comprising a face-cam and a peripheral cam, both 5 cams rotating in unison, the cams being engaged by arms on the carriage, and means for imparting an intermittent rotary motion to the said cams from the note-sheet, the said means comprising a ratchet-wheel on the cams, 10 a pawl for the ratchet-wheel, a pneumatic on the pawl, an air-chamber open to the atmosphere and connected with the pneumatic, a pressure - chamber connected with the air-

chamber, a valve mechanism for controlling the connection between the chambers, and a 15 lever on the carriage, engaging the said valve mechanism, the lever being controlled by the note-sheet, as set forth.

In testimony whereof we have signed our names to this specification in the presence of 20 two subscribing witnesses.
